UNITED STATES PATENT OFFICE.

WILLIAM ABERCROMBIE DUNN, OF SMITHVILLE, MINNESOTA, ASSIGNOR OF
ONE-HALF TO ATHOL MORTON MILLER, OF DULUTH, MINNESOTA.

ROLLER-MILL AND CUTTER.

SPECIFICATION forming part of Letters Patent No. 709,084, dated September 16, 1902.

Application filed January 3, 1902. Serial No. 88,305. (No model.)

To all whom it may concern:

Be it known that I, WILLIAM ABERCROMBIE DUNN, a citizen of the United States, residing at Smithville, in the county of St. Louis and 5 State of Minnesota, have invented certain new and useful Improvements in Roller-Mills and Cutters; and I do hereby declare the following to be a full, clear, and exact description of the invention, such as will enable others 10 skilled in the art to which it appertains to make and use the same.

This invention relates to an improved machine or mill designed for the construction of finished rolled-metal T-beams or angle beams 15 or bars.

The object of the invention is the production of the said types of beams or bars from rolled I-beams and channel-beams, and while my improvements are applicable to the making 20 of what are known as "T's" and "angles" from I-beams and "channels" constructed by the processes at present practiced the said improvements are designed more especially for use in connection with 25 the process and apparatus for the manufacture of I-beams and channels which form the subjects-matter of my applications for patents, filed January 3, 1902, Serial Nos. 88,301 and 88,302.

30 The nature of my present improvements will be readily comprehended, reference being had to the following detailed description and to the accompanying drawings, in which—

Figure 1 is an elevation of machine or mill 35 embodying my invention and designed to form T's from I-beams. Fig. 2 is a similar view, partly broken away, of a mill for forming angles from channel-beams. Fig. 3 is an enlarged sectional view, partly broken away, 40 showing the construction of the rolls and the severed T's. Fig. 4 is an enlarged sectional view of the finished angles. Fig. 5 is an elevation of a channel-finishing machine.

Referring to the drawings by numerals, 1 45 denotes the type of finishing-machine which I prefer to employ in connection with the process and apparatus for making channel-beams hereinbefore referred to, it being understood that for finishing I-beams a modification of 50 the shape of the rollers is alone necessary. In the making of T's and angles, respec-

tively, from I-beams and channels I employ a mill constructed substantially similar to that illustrated in Fig. 5, with the difference that centrally of the rolls I provide cutter-blades, which in practice operate to sever the beam centrally to form T's or angles, dependent upon the type of beam furnished. My present invention is more particularly concerned with the construction of cutter-blade 60 employed, although a feature of the improvement is the combination of cutter-blades with rolls designed to "finish" the product as it is severed.

Referring to Figs. 1 to 4, inclusive, 2 denotes the frame of the mill, in which is mounted a lower roll 3 and an upper roll 4, the latter being vertically adjustable by the means shown at 4'. These rolls preferably constitute the finishing-rolls, it being understood 70 by reference to my other applications hereinbefore referred to that the finishing-rolls are employed for the final pass of the metal. The shape of the rolls is governed by the form of the beam, Fig. 2 showing rolls for channels 75 and Fig. 3 the rolls for I-beams. Centrally of the rolls 3 4 are the cutter-blades 5 5, each provided with two outer annular cutting edges 6 6 and an intermediate concave periphery 7. In practice the rolls are adjusted to provide a very slight clearance between the cutting edges of the two blades, whereby the beam in passing between the rolls is practically severed, as illustrated more clearly in 80 Fig. 3. The inner ends of the T's or angles, 85 as the case may be, are by the peculiar form and action of the coöperating blades provided with a finished surface, needing no dressing or other further treatment, and by reason of the intermediate concave peripheries of the 90 blades the central cut-away portion 8 of the beam receives such a shape in cross-section as enables it subsequently to be readily rolled into rods of circular or other form.

It will be understood from the foregoing 95 that simultaneously with the operation of severing the I-beams or channels into T's or angles the operation of finishing is accomplished in a manner similar to that performed in the finishing-machine illustrated in Fig. 100 5, so that the one mill performs the double function of finishing the beam and dividing

it longitudinally to form the T's or angles. This provision reduces the number of passes of the metal, thereby diminishing the cost of production and increasing the capacity, and, 5 moreover, by the peculiar form of cutter-blade employed not only is the T or angle finished throughout, but there is saved the central portion, which heretofore has been incapable of utilization.

10 I claim as my invention—

1. The combination of a pair of rolls for finishing a shaped flanged beam having cylindrical web-rolling portions, cutter-blades on the rolls between the cylindrical web-rolling portions, each blade having two closely-adjacent cutting edges, the outer faces of which are at a right angle to said cylindrical web-rolling portions for producing finished edges on the finished severed portions of the 15 beam.

2. The combination of a pair of rolls for finishing a shaped flanged beam having cylindrical web-rolling portions, cutter-blades on the rolls between the cylindrical web-rolling portions, each blade having two closely-adjacent cutting edges, the outer faces of which are at a right angle to said cylindrical web-rolling portions for producing finished edges on the finished severed portions of the beam, and the inner faces of which cutting edges are beveled and provide a concave rolling-surface for shaping the intermediate severed portion for further treatment. 25

In testimony whereof I affix my signature in presence of two witnesses.

WILLIAM ABERCROMBIE DUNN.
